CLAIM

The ornamental design for a shoe as shown and described.

DESCRIPTION

FIG. 1 is a front perspective view of a shoe showing my new design;
FIG. 2 is a side view thereof; and,

FIG. 3 is a rear perspective view thereof.

The broken lines immediately adjacent to the shaded area define the bounds of the claimed design and form no part thereof. The broken line showing of the smaller triangular shaped element within the shaded larger triangular shaped region forms no part of the claimed design. The contrast in shading between the large triangular region and the regions adjacent thereto represents a contrast in appearance only. The broken lines depicting the remainder of the shoe form no part of the claimed design.
